UNITED STATES PATENT OFFICE

IRWIN A. SEVERSON, OF SOLDIER, IOWA

TWINE IMPREGNATING DEVICE

Application filed June 11, 1931. Serial No. 543,695.

The present invention relates to a twine impregnating device and has for its primary object to provide, in a manner as hereinafter set forth, a device of this character for mounting on a binder between the twine box and the needle for impregnating the twine with an insect proof or repelling solution as the twine is used.

Other objects of the invention are to provide a twine impregnating device of the character described which will be simple in construction, strong, durable, efficient and reliable in operation and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a twine impregnating device constructed in accordance with the present invention.

Figure 2 is a view in end elevation of the device.

Figure 3 is a view in vertical longitudinal section through the device.

Figure 4 is a view in vertical cross section through the twine impregnating device.

Figure 5 is a detail view in horizontal cross section through the applicator wheel supporting bracket looking upwardly.

Referring now to the drawings in detail, it will be seen that the reference numeral 1 designates a metallic plate which is substantially rectangular in plan and which is secured in position on the binder by one or more brackets 2 of suitable form and the bolts 3.

Formed integrally with the plate 1 adjacent a margin thereof is a depending flange 4 over which fits the upper portion of an open topped solution receiving tank or container 5. Upstanding bolts 6 are rigidly mounted

on the inner sides of the end walls of the tank 5 and project thereabove for insertion through openings provided therefor in the end portions of the plate 1. Nuts 7 being threaded on the upper end portions of the bolts for securing the tank to the plate.

On one side the plate 1 is formed to provide a raised portion constituting a housing 8 which is open at its top and which is provided with a lid or closure 9 which is hingedly mounted at one end, as at 10. The free end portion of the lid or closure 9 is provided with a shoulder or abutment 11 and mounted for swinging movement on the corresponding end portion of the housing 8 is a resilient yoke 12 having inturned end portions forming trunnions 13 (see Figure 3) which are journaled in openings provided therefor in the housing 8. The resilient yoke 12 is adapted for the swinging movement over the free end portion of the lid or closure 9. An arcuate latch lever 14 of sheetmetal is mounted for swinging movement on the right portion of the yoke 12, said latch lever having apertured ears 15 on an intermediate portion through which the yoke passes. The lever 14 is operatively engageable with the shoulder or abutment 11 for releasably securing the lid or closure 9 in closed position.

A pivot pin 16 extends transversely through the hinged end portion of the lid or closure 9 and mounted for swinging movement thereon is a pair of arms 17 between the free end portions of which extends a journal pin 18. A pressing roller 19 is mounted for rotation between the arms 17 on the pin 18. A bar 20 extends between intermediate portions of the arms 17 for operatively connecting a rod 21 thereto. The bar 20 is mounted for rocking movement on the arms 17. The rod 21 extends slidably through an opening provided therefor in the lid or closure 9. A coil spring 22 encircles the rod 21 and has one end engaged with the lid or closure 9 and the other

end engaged with the bar 20 for yieldingly urging the roller 19 downwardly.

A metallic bracket 23 is rigidly secured to the lower side of the plate 1 within the flange 4 and depends from said plate into the tank 5. In the present instance the bracket 23 is secured to the plate 4 by the same bolts which secure said plate to the bracket 2. Projecting laterally from the lower end portion of the bracket 23 beneath the housing 8 is a spindle bolt 24 upon which the applicator wheel 25 is journaled. The applicator wheel 25 is formed with the peripheral marginal flanges 26 and an annular pad of suitable compressible absorbent material 27 is mounted on the periphery of the wheel 25 between the flanges 26. On one side the applicator wheel is formed to provide a transverse opening or channel beneath the pad 27 for the reception 20 of wood block 28 for securing the pad on the wheel. Suitable securing elements, such as tacks may be driven through the pad into the block. The pad may, of course, be in the form of a strip prior to its mounting on the applicator wheel. The roller 19 is adapted to contact with the pad 27 between the flanges 26.

The end walls of the housing 8 are provided with openings in which are mounted 30 the guides 29 through which the twine 30 passes. The twine 30 passes between the roller 19 and the applicator wheel 25 and is pressed into the resilient absorbent pad 27 by said roller 19.

In use, the twine, when passing from the twine box of the binder to the needle passes through the housing 8 and, as before stated, is engaged against the felt pad 27 by the roller 19, thereby frictionally driving the applicator wheel 25 which has its lower portion immersed in the solution in the tank. It will thus be seen that the pad 27 will be constantly saturated with the solution when the device is in use and the twine 30 being pressed 45 into the pad 27, will be thoroughly impregnated with the solution. The lid or closure 9 provides means through the medium of which convenient access may be had to the interior of the device for any desired purpose, as for replenishing the solution in the tank.

It is believed that the many advantages of a twine impregnated device constructed in accordance with the present invention will be 55 readily understood, and although the preferred embodiment of the invention is as illustrated and described, it is to be understood that changes in the details of construction and in the combination and arrangement 60 of parts may be resorted to which will fall within the scope of the invention as claimed.

What is claimed is:—

In a structure of the character described, 65 a container having a closure, a wheel rotatably mounted within the container and hav-

ing a pair of axially spaced radial flanges defining an intervening groove, a layer of absorbent material in said groove, a roller between said flanges and engaging said layer of absorbent material, an arm pivotally carried by said closure and supporting said roller, and resilient means associated with said arm and closure for urging said roller into contact with said layer of absorbent material.

In testimony whereof I affix my signature. 75

IRWIN A. SEVERSON.
